his Attorney.

UNITED STATES PATENT OFFICE.

WILLIAM C. ROLLINS, OF MINNEAPOLIS, MINNESOTA, ASSIGNOR OF ONE-THIRD TO E. A. WEDEN AND ONE-THIRD TO J. H. SMALLEY, BOTH OF MINNEAPOLIS, MINNESOTA.

SPARK-PLUG.

1,333,037.

Specification of Letters Patent. Patented Mar. 9, 1920.

Application filed August 2, 1917. Serial No. 184,044.

To all whom it may concern:

Be it known that I, WILLIAM C. ROLLINS, a citizen of the United States, residing at Minneapolis, in the county of Hennepin and State of Minnesota, have invented certain new and useful Improvements in Spark-Plugs, of which the following is a specification.

My invention relates to spark plugs and has for its object to provide a substantially uniformly cylindrical insulating member which is clamped at its lower edge in a metallic base or receptacle against an annular flange near the end thereof by a cap screwable upon the exterior of said receptacle to almost completely incase said insulating member. A still further object is to construct the insulator with a cavity on the interior and a spherical projection on the exterior to prevent jumping across of the spark. A still further object is to form one or more of the spark gap members integral with the receptacle.

The full objects and advantages of my invention will appear in connection with the detailed description thereof and are particularly pointed out in the claim.

In the drawings, illustrating the application of my invention in one form,—

Figure 1 is a side elevational view of the spark plug. Fig. 2 is an end view of the same looking toward the spark gap end; Fig. 3 is a longitudinal section taken substantially on line 3—3 of Fig. 2.

My invention which is best shown in Fig. 3 comprises an outer shell or receptacle 10, which is internally bored at 11 to form a shoulder 12 near the extreme end thereof. Within this receptacle is positioned a cylindrical insulator 13 which may be made of porcelain or any other suitable insulating material. This insulator is made hollow at its lowermost extremity 14 leaving a lip 15 extending completely about the same. At its upper end insulator 13 is formed with a spherical protrusion 16 which extends to within a short distance of the circumference of the same forming an annular shoulder 17. A cap 18 is made screwable upon the end of the receptacle 10 at 19 and is constructed with a flange portion 20 which engages shoulder 17 of insulator 13 and forces said insulator against a gasket 21 placed between the lip 15 of said insulator and the aforementioned flange 12. This makes a

tight joint which eliminates leakage. If desired a gasket 22 identical with gasket 21 may be used between shoulder 17 on insulator 13 and cap 18 although the same is not absolutely necessary. It will be noted that both of these gaskets are positioned toward the ends of the members 10 and 18 so that the same may be readily picked loose in case of replacement. Again, the gaskets when once loosened almost drop out as they do not have to pass a series of threads as in the ordinary forms.

Through the center of the insulator 13 runs a rod 23 which serves as one of the spark gap members and which is held in place at one end by a shoulder 24 formed thereon which lodges in cavity 14 and at the other end by a lock washer 25 which rests on protrusion 16 and a nut 26 screwable upon the end of said rod. A thumb nut 27 serves to hold the lead terminal from the sparking system in the usual manner. The other members of the spark gap are constructed integral with receptacle 10 as follows: The interior of the plug is bored conical at 28 and is turned curved on the exterior at 29 or turned to any other suitable shape. The receptacle 10 is then mounted in a milling machine and two parallel cuts taken with a cylindrical miller at 30 and 31 as is clearly indicated in Fig. 2. This leaves two pointed prongs 32 and 33 which approach each other in the center on opposite sides of the rod 23 which is constructed long enough at 34 to extend beyond the same. With this construction adjustment of the gap is hardly necessary as the portion 34 of member 23 is very short and as the insulator 13 has a long cylindrical portion which will hence tend to center itself in the smooth bore of the receptacle 10.

The exterior of the plug is formed with a hexagonal wrench head 35 and a flange 36 and is further threaded at 37 for attachment to any of the ordinary forms of engines.

The advantages of my invention are manifest. The device is very simple in construction and effective in operation. Repairs and cleaning can be easily made and due to the self centering of the insulator only that portion need be removed from the engine for cleaning which greatly simplifies the operation. Breakage or crackage of the insulator is prevented due to the uniformity of di-

ameter of the insulator and the relative size of the same compared to the rest of the plug.

I claim:

- 5 A spark plug comprising an outer shell having a uniform bore, an annular flange at one end of the bore, a pair of opposed spark gap members extending toward each other from said flange, an insulating member fitting within said bore having a concave recess at one end whereby a lip is formed at the end of said insulating member adapted to rest upon said flange, a sin-
- 10

gle spark gap member extending longitudinally through said insulating member and 15 having one end lying between the aforesaid pair of spark gap members, said single spark gap member consisting of a rod having a shoulder resting upon the wall of said concave recess, and a cap screwable upon the other end of said shell, said cap having an annular flange adapted to engage said insulating member.

In testimony whereof I affix my signature.

WILLIAM C. ROLLINS.
